WATER FOUNTAIN

John O. Hruby, Jr., 1240 Alta Paseo,
Burbank, Calif. 91501

Filed July 6, 1962, Ser. No. 70,816

Term of patent 14 years

(Cl. D91—4)

FIG. 1 is a perspective view of a water fountain showing my new design and showing in broken lines a catch basin and a fountain producing device which are only included for illustrative purposes; and

FIG. 2 is a cross-sectional view thereof taken on line 2—2 of FIG. 1.

I claim:

The ornamental design for a water fountain as shown and described.
